SUCTION OPERATED FLOOR CLEANING
DEVICE EMPLOYING LIQUID

Frederick K. Minerley, Chicago, Ill.

Application April 24, 1946, Serial No. 664,626

5 Claims. (Cl. 15—320)

1

This invention relates to suction cleaners, but more particularly to cleaners of this type adapted for use in cleaning floors.

It has long been recognized that the cleaning of floors, such as tile, linoleum, marble or terrazzo floors, is an arduous and dirty job, particularly in the home. Ordinarily, cleaning is accomplished by the use of a sponge, mop, or the like, recurrently doused in water and squeezed dry after a small area has been scrubbed. Manifestly, this is an exceedingly tiring operation, and it is, therefore, a desideratum to provide a tool by which the liquid can be delivered to the floor surface, the scrubbing of the floor accomplished, and thereafter the water or other liquid removed from the floor surface. Very definite need exists for a relatively simple and inexpensive tool of this character which can be conveniently used in the home as well as elsewhere for this purpose.

An object is to produce a simple and efficient hand tool which can be conveniently manipulated to cause liquid, such as water, to be delivered to the floor surface, which then can be operated preferably from a standing position, expeditiously to scrub the floor surface, and which then can be operated to suck or draw the liquid and dirt carried thereby from the floor so that the floor surface is left clean and practically dry.

Other objects and advantages of the invention will hereinafter appear and for purposes of illustration but not of limitation, an embodiment of the invention is shown on the accompanying drawings, in which

Figure 1 is a side elevation of a cleaning tool particularly adapted for scrubbing or cleaning a floor surface;

Figure 2 is an enlarged fragmentary longitudinal section elevation of a portion of the tool shown in Figure 1, the valve mechanism being actuated to enable the liquid to be discharged or to flow therefrom to the floor surface;

Figure 3 is a view similar to Figure 2, but showing the valve mechanism in such position that the flow of liquid to the floor surface is shut off and also showing the vacuum or suction controlling valve in closed position, the tool thus being in condition to be used for scrubbing purposes;

Figure 4 is a view similar to Figures 2 and 3 but showing the valve mechanism actuated to close off the flow of liquid and enabling the suction to be rendered effective for sucking or drawing the liquid from the floor surface; and

Figure 5 is a bottom plan view of the floor tool.

The illustrated embodiment of the invention comprises a tool for use in connection with the

2

scrubbing or cleaning of floors, the same being adapted for the cleaning of linoleum, tile floors or the like, as well as carpeted floors or other similar floor covering. In this instance, the tool is adapted to be connected by a flexible hose 10 to a portable type vacuum cleaner, or other suction producing source. As shown, the flexible hose is detachably connected to an elongate tube or wand 11, the upper end portion of which is curved in one direction and the lower end portion of which is curved in the opposite direction, the central portion of the tube being substantially straight.

Detachably connected to the lower or outwardly curved end of the wand 11 is a floor tool 12 which, in this instance, is hollow and is provided with downwardly extending bristles 13 disposed in a substantially annular or oblong row, to the center of which a passage 14 leads so that liquid may pass in one direction or the other through the tube 11 with respect to the floor tool 12. As shown in Figure 5, within the row of bristles is an oblong squeegee 13'. It is to be understood that other forms of floor tools may be provided, such, for example, as rubber sponges, sponge fabric or the like such as may be necessary or desirable for use in the scrubbing or cleaning of hard floor surfaces or carpeted surfaces.

Manifestly, the tube 11 is hollow throughout its length and along one side of the tube are formed three apertures to receive tubes 15, 16 and 17, in the form shown, the tubes being spaced substantially equidistantly from each other. The opposite ends of the tubes 15, 16 and 17 extend through apertures in an elongate tank 18, it being understood that the tubes 15, 16 and 17 are suitably secured to the wand and tank in substantially fluid-tight relation and constitute fluid connections. Tube 15, it will be observed, extends inwardly at the tank, the inner end functioning as a baffle, whereas the outer end of the tube is closed against the inner wall of wand 11. An opening 15a is formed near the outer end of tube 15 to bring the bore of the tube in communication with the bore of the upper end of the wand. The lower end of the tank 18 is closed and the upper end is open but threaded to receive a screw-threaded cap 19. The passage in the tube or wand 11 directly above the short tube 16 is closed by a partition member or plate 20.

The source of suction is rendered effective and ineffectible by a disc valve 21 having a sliding fit with the inner end of the small tube 15 for the control of air from tank 18 to the wand 11. The

stem 22 of the valve extends through a wall of the wand 11 and is adapted to be engaged by actuating rod 23, a coil spring 24 encircling the stem 22 being interposed between the wand 11 and a disk 24 affixed to the outer end of stem 22. The spring 24 normally holds the valve 21 in position to uncover the hole 15a.

A means for controlling the passage of liquid from tank 18 to tube 11 constitutes valve 25 adapted to seat against the end of the tube 17 within the tank 18. The stem 26 of the valve 25 extends through the tube 17 and the outer wall of the wand 11 to be engaged by the opposite end of the actuating rod 23. A spring 27 encircles the valve stem 26 and is interposed between the wand 11 and a disc 26a fixed to the end of stem 26. Spring 27 normally holds valve 25 seated.

Disposed intermediate the ends of the rod 23 and secured to the wand 11 is a bracket 28 which, in this instance, is formed with a longitudinally elongate slot to receive pins 29 projecting laterally from the sides of the rod 23, it being understood that the bracket 28 consists of a pair of spaced outwardly extending plates. Disposed between the plates of the bracket 28 is a bell crank arm 30 pivotally mounted at 31, the bar engaging end of the bell crank extending in a direction away from the floor tool and having a roller 32 for contacting the bar 23.

The bell crank 30 is actuated by means of a wire link 33 which is connected to the outstanding arm of the bell crank and to an actuating handle 34 pivoted to the upper end portion of the wand 11.

In operation it will be understood that a small quantity of liquid such as water containing, as desired, a suitable detergent is introduced into the tank 18 after the cap 19 is first unscrewed. The water or liquid level within the tank should not extend above the tube 16 so that the upper portion of the tank, i. e. the portion above the liquid level, may function as a vacuum or plenum chamber, as detailed below.

In use and assuming that the suction or partial vacuum is created through the instrumentality of the flexible hose 10, a stream of air would normally pass through the floor tool 12, up the front end portion of the wand 11 to the tube 16, thence laterally into the tank 18 and through the upper portion of the tank to the tube 15, and thence past to the valve 21 to the upper portion of the wand 11. When the operating handle 34 is released, the valves are in the position shown in Figure 4, in which the liquid controlling valve 25 is in closed position and the vacuum controlling valve 21 is in open position.

When it is desired to flow a quantity of liquid on the floor surface, the operating handle 34 is actuated to rock the bell crank 30 in a counter-clockwise direction to tilt or actuate the bar 23 to the position indicated in Figure 2, at which time the vacuum controlling valve 21 is closed and the liquid valve 25 is open. At that time, the liquid may flow from the tank 18 by gravity, through the tube 17 and the lower end of the wand 11 to the floor tool 12. So long as the valve 25 is open and the valve 21 closed, liquid will flow by gravity inasmuch as tank 18 is then not under sub-atmospheric pressure.

By slightly releasing the operating handle 34 to the point that the vacuum controlling valve 21 is closed and the spring 27 has operated to close the liquid valve 25 (Figure 3) then the tool may be used for scrubbing purposes without additional flow of liquid, and the liquid on the floor

may be brushed or scrubbed into the floor surface to collect the dirt and other foreign particles. In this connection, it is desirable that the weaker spring be the spring 24 associated with the vacuum controlling valve 21. Thus by rocking the bell crank 30, it is possible to actuate the bar 23, close the valve 21 while the valve 25 remains closed, this being due to the point of engagement of the bell crank 30 with the bar, and the spring arrangement.

After the floor surface has been sufficiently scrubbed, then by releasing the control handle 34 so as to secure the benefit of the partial vacuum or suction created from the flexible tube 10, the spring 24 moves the vacuum controlling valve 21 to open position and the spring 21 moves the valve 25 to its closed position so that the dirt carrying liquid will be drawn through the floor tool 12, through the wand 11, and into the tank 19 through the tube 16. The upper portion of the tank 19, in view of the fact that it is a much larger area than the wand 11, provides a pressure reducing, expansion or plenum chamber. As a consequence, the liquid and dirt or foreign particles carried by the stream of air will fall into the tank while the stream of air continues in the manner above described. The stream of air passing at relatively high velocity together with entrained liquid and foreign matter is thrown somewhat against the walls of the upper portion of the tank and these heavier foreign particles and liquid flow or drop into the lower portion of the tank. The importance of having a portion of the tube 15 projecting inside of the tank resides in the fact that it acts as a baffle for militating against moisture passing along with the air to the wand 11. When the liquid becomes dirty, it may be emptied from the tank 18 and replaced by clean liquid.

It should be understood that the cleaning operation can be effectively carried on on carpets or rugs as well as on hard surfaces such as linoleum or tile surfaces, and in this manner, a substantial area can be quickly and efficiently cleaned and left practically dry. Although some moisture will necessarily remain on the floor surface, it is only a negligible quantity which will quickly evaporate. Although the tool described herein is in the nature of an accessory to a vacuum cleaner, the vacuum creating mechanism may be mounted on the tool thereby providing a self-contained unit.

It is manifest that, in following the above teachings, various modifications of the baffle, valves, valve control mechanism, and other features, including details of construction, arrangement, and operation may be effected without departing from the spirit of the invention, especially as defined in the appended claims.

What I claim is:

1. A floor cleaner comprising a floor tool, a support for said tool comprising a single elongate pipe extending upwardly therefrom, a container supported on said pipe, said container having upper and lower portions, the lower portion being adapted to contain liquid, a first fluid connection with the upper portion of said container adapted for coupling with a source of suction, a second fluid connection between the upper portion of said container and said pipe whereby air and liquid drawn upwardly through the pipe will pass into the container, a third fluid connection between the lower portion of said container and said pipe and establishing a gravity flow connection from said lower portion

of the tank to said pipe, means on said cleaner for selectively rendering said suction effective and ineffective, and valve means in said third fluid connection for selectively opening and closing the same whereby, when the third fluid connection is open, liquid may flow from the lower portion of the tank to the pipe under the influence of gravity.

2. A cleaner of the character described comprising a floor tool, a substantially rigid tubular support connected to and extending generally upwardly from the floor tool when the latter is in normal use, a tank adapted to contain liquid in the lower portion thereof mounted on said tubular support above the floor tool, said tubular support having a hollow bore communicating with the interior of the tank below the liquid level providing a passage from said tank to the floor tool enabling gravitational liquid flow to the latter, valve means controlling said passage, a fluid connection between the hollow bore of said support and the tank above the liquid level therein, the upper portion of the tank providing an expansion chamber, means providing a passage connected to said tank at a point spaced above said fluid connection adapted to be connected to a suction source, valve means controlling said last passage, and means for jointly actuating said valve means.

3. A floor cleaner comprising a floor tool, a support for said tool comprising a single elongate pipe extending upwardly therefrom, a container supported on said pipe, said container having upper, lower, and intermediate portions, the lower portion being adapted to contain liquid, a first fluid connection with the upper portion of said container adapted for coupling with a source of suction, a second fluid connection between the intermediate portion of said container and said pipe, a third fluid connection between the lower portion of said container and said pipe and establishing a gravity flow connection from said lower portion of the tank to said pipe, means on said cleaner for selectively rendering said suction effective and ineffective, and valve means in said third fluid connection for selectively opening and closing the same whereby, when the third fluid connection is open, liquid may flow from the lower portion of the tank to the pipe under the influence of gravity.

4. A cleaner of the character described comprising, a floor tool, a substantially rigid tube connected to said floor tool and leading therefrom in the direction which is upwardly therefrom when said tool is applied to a floor, means forming an enclosure supported on said tube above said floor tool, said enclosure having a

lower portion constituting a liquid reservoir and an upper portion constituting an expansion chamber, first and second fluid connections respectively between the lower ends of said lower and upper portions of said enclosure and said tube, and a third fluid connection leading from said upper portion adapted for coupling to a source of suction, first valve means in said first fluid connection for selectively opening and closing said first fluid connection, second valve means in said third fluid connection for selectively rendering said suction ineffective and effective, and control means movable between a plurality of positions for alternately operating said first and second valve means selectively to open said first fluid connection so as to enable liquid to flow gravitationally from said lower portion through said tube to said tool while rendering said suction ineffective when in the first of said positions and, when in the second of said positions for closing said first fluid connection to prevent liquid flow therethrough while operating said second valve means so as to render said suction effective.

5. The combination claimed in claim 4, said control means being movable to a third of said plurality of positions in which said first valve means is closed and said second valve means is operated to render said suction ineffective.
